UNITED STATES PATENT OFFICE

FREDERICK MARSHALL, OF PITTSBURGH, PENNSYLVANIA

HEATING BAG

Application filed March 1, 1932. Serial No. 596,044.

The conventional heating bag is of oblong shape with a plugged opening in one end and is formed of soft rubber. Thus the bag is not self-sustaining and if otherwise unsupported lies on one of its sides.

Thus if the bag is to be placed against the feet or another portion of the body of the user it is necessary to support it in place as by a pillow or by wadding up the bedclothes.

10 The principal object which I have in view is the provision of a self-supporting heating bag which when placed against the feet or other portion of the human body will hold its position and maintain contact without

15 other support.

For this purpose I have invented a container which is provided with an extended base of sufficient stiffness to prevent its folding up and which forms the support of the heating bag. Rising from the base is a hollow container for containing the water or other heating fluid, which container is so constructed to substantially maintain its contour when filled with the water.

20 25 The bottom of the container is preferably formed by the base itself and the container is of oblong shape with substantially vertical end walls. The front wall of the base approaches the vertical but preferably inclines slightly rearwardly, while the rear wall of the base inclines forwardly and upwardly to the top of the container.

30 35 One of the end walls has a filling and emptying opening which is provided with a water-tight screw plug or other suitable stopper.

Both end walls may be provided with means for grasping the container, such as suitable handles, which may be exterior and horizontally disposed ribs.

40 45 Any suitable material may be used for the container, such for instance as metal, but I prefer to use rubber, the base being sufficiently stiff to keep its shape and properly support the bag while the walls of the bag itself may be of softer rubber, so that the bag may be folded substantially flat on the base when not in use. To maintain the desired contour of the bag when it is filled I prefer to provide the front and rear walls and top with

50 55 suitable stiffening means. Such means may

be in the form of ribs extending vertically from the base up the front and rear walls and crossing the top of the bag.

Other novel features of construction and also of arrangement of parts will appear 55 from the following description.

In the accompanying drawing, wherein I have illustrated a practical embodiment of the principles of my invention, Fig. 1 is an end elevation of the hot water bag.

60 Fig. 2 is a front elevation of the same.

Fig. 3 is a top plan view of the same.

Fig. 4 is a vertical section taken along the lines 4-4 in Fig. 3.

65 Referring to the drawing, 1 represents the flat base, which may be of a general rectangular shape and may be provided with a hole 2 by means of which the bag may be hung up when not in use. The container proper is formed of two, preferably vertical, end walls 70 3 and a front wall 4 which rises from the base and which may be vertical, but which is preferably slightly inclined upwardly and rearwardly, as shown in Figs. 1 and 4. 5 represents the rear wall which also rises from 75 the base and has a greater inclination, converging upwardly towards the front wall and the walls united by the curved top 6.

7 represents stiffening ribs which extend from the base up the front wall around over 80 the top and down the rear wall to the base. One of these ribs is preferably provided at each end of the bag and a third in the center. Each of the end walls is provided with a handle or horizontally disposed rib 8 by 85 means of which the bag may be conveniently lifted. One of the end walls, at a point near its top, is provided with an opening for filling and emptying, and said opening is provided with a neck 9 in which is screwed a 90 stopper 10.

When the bag is made from rubber or similar material the necessary stiffness in the base may be obtained by embedding therein the required number of layers of fabric 11, in 95 much the same manner as the outer casings of automobiles are reinforced and made stiff, and like layers of fabric may be embedded in the ribs 7, as indicated at 12.

The base should be extended toward the 100

front and rear beyond the walls 4 and 5 to a sufficient extent to give a firm stance for the heating bag and to prevent the same being tipped over. When the hot water bag is used 5 the heels of the user rest upon the base and thus help in anchoring the bag in place. The tendency to tip is further counteracted by the fact that the front and rear walls of the bag converge upwardly, thus providing a cross 10 sectional area of substantially triangular shape, which adds greatly to the stability of the bag.

The base may also be extended to a limited 15 degree beyond the end walls, which will also provide a greater degree of stability.

The idea of providing a front wall which 20 approaches the vertical or has a relatively slight angle of convergence toward the rear wall is to provide a contact surface for the 25 feet of the user which will be disposed at the proper angle to maintain surface contact over substantially the sole area of the feet. If a greater inclination is desired the heating bag is applied to the feet with the wall 5 against the soles.

My improved heating bag is much more 30 convenient to use and its heating effect is more fully realized than is possible in the case of the conventional heating bag now in general use.

I have described and illustrated the embodiment of my invention as a hot water bag 35 but it will be understood that any suitable and convenient source of heat or heating agent may be employed.

I claim:—

1. A heating bag comprising a triangularly prismatic container of flexible waterproof material having one of its sides laterally extended in both directions to form a base on which the remainder of the bag is collapsible, and reinforcing ribs extending transversely around the remaining sides of the container to assist in holding the container in prismatic 45 form when filled and to prevent direct contact of the foot soles with the body of the container.

2. A heating bag comprising a triangularly prismatic container of flexible waterproof 50 material having one of its sides laterally extended in both directions to form a base on which the remainder of the bag is collapsible, and reinforcing and stiffening means embedded in the basal side of the container.

55. Signed at Pittsburgh, Pa., this 26th day of February, 1932.

FREDERICK MARSHALL.
